UNITED STATES PATENT OFFICE.

BARNET SHAPIRO, OF SEA GATE, NEW YORK, ASSIGNOR TO HIGHTSTOWN MFG. CO., INC., OF HIGHTSTOWN, NEW JERSEY, A CORPORATION OF NEW JERSEY.

DESIGN FOR LACE.

61,401.

Specification for Design.

Patented Aug. 22, 1922.

Application filed April 26, 1922. Serial No. 1,971. Term of patent 14 years.

To all whom it may concern:

Be it known that I, BARNET SHAPIRO, a citizen of the United States, and a resident of Sea Gate, Coney Island, in the county of Kings and State of New York, have invented a new, original, and ornamental Design for Lace, of which the following is a specification, reference being had to the accompanying drawing, forming part thereof.

The drawing is a plan view of a piece of lace embodying my new and original design.

I claim:

The ornamental design for lace, as shown.

BARNET SHAPIRO.
